UNITED STATES PATENT OFFICE.

GOODRICH Q. LEWIS, OF WHEATON, ILLINOIS, ASSIGNOR TO WILLIAM H. MINER, OF CHAZY, NEW YORK

REFRIGERATOR-CAR-DOOR-LOCKING MECHANISM.

1,140,517.

Specification of Letters Patent. Patented May 25, 1915.

Application filed July 25, 1914. Serial No. 858,246.

To all whom it may concern:

Be it known that I, GOODRICH Q. LEWIS, a citizen of the United States, residing at Wheaton, in the county of DuPage and State of Illinois, have invented a certain new and useful Improvement in Refrigerator-Car-Door-Locking Mechanism, of which the following is a full, clear, concise, and exact description, reference being had 10 to the accompanying drawings, forming a part of this specification.

This invention relates to improvements in refrigerator car door locking mechanism.

In loading and unloading refrigerator cars near platforms, it has been found that much difficulty has been encountered in swinging the door open when the car is adjacent the platform, for the reason that the platform is generally constructed on a 15 level with the floor level of the car in order to facilitate trucking. In such circumstances, the door locking shaft having the crank arms at the ends thereof necessarily extended beyond the upper and lower edges 20 of the door, encounters the platform, and the door cannot be opened unless the platform is chopped away to provide the necessary clearance for the lower ends of the door operating shafts. Not only is this a great 25 inconvenience, but considerable time and labor is lost in chopping away the platform to provide the clearance for the shafts, and the platforms are seriously injured.

The object of my invention is to provide 30 means in connection with the most common form of refrigerator car door operating shaft which will overcome the objections above indicated, and to provide such means at practically no additional expense.

40 In the drawings forming a part of this specification, Figure 1 is a side elevation of a portion of a refrigerator car and door, showing my improvements in connection therewith, the doors being in closed position; Fig. 2 is a horizontal sectional view taken substantially on line 2—2 of Fig. 1, and showing one of the doors in partly 45 opened position in dotted lines; Fig. 3 is an enlarged vertical sectional view taken substantially on line 3—3 of Fig. 1; and Fig. 4 is a view somewhat similar to that of Fig. 1, but showing the door carrying the shaft in slightly opened position after the shaft has been disengaged from the keepers and raised 55 to its clearing position.

In said drawing, 10 denotes the frame members of the car to which the doors 11 and 12 are pivotally connected, as by hinges 13—13. The door 12 carries operating shaft A, described more in detail hereinafter, and the door 11 carries the latch 14 for the lever or arm 15 pivotally connected to the shaft A, as at 16, and by which the shaft is operated.

The shaft A comprises an intermediate 65 member 17 of rectangular, preferably rolled stock, to which are secured, at its ends, two similar crank members 18—18, each of which is slotted, as indicated at 19, to receive therein the ends of the member 17, the latter being 70 secured to the crank members 18 by rivets or other suitable fastening devices 20—20. Each crank member 18, which may be in the form of a casting, has an off-set crank pin 21 and an elongated journal 22, the journal portions 22—22 being mounted in suitable bearings 23—23 secured to the door 12. As clearly shown in Figs. 1, 3 and 4, the journals 22—22 are considerably longer than the bearings 23—23, so that the shaft A is permitted longitudinal movement therein. The 75 crank pins 21—21 engage and coöperate with keepers 24—24 secured to the upper and lower members of the door frame, one of said keepers being shown in plan in Fig. 2. 80 As shown in said figure, each keeper 24 is provided with two, annularly arranged, cam faces 25 and 26, the latter coöperating with the crank pins 21 in closing the doors, and the former coöperating with the crank pins 90 21 to open the doors, in a manner well understood. Also mounted on the door 12, between the shaft A and the free edge of the door and just below the lever 15 when the latter is in position shown in Fig. 1, is a 95 bracket 27 having a curved bearing portion 28 on the upper end thereof, said bearing 28 serving as a fulcrum for the lever 15 to lift the shaft A vertically to the position shown in Fig. 4.

In operating the device, the lever 15 is first released by moving the latch 14, and the shaft A rotated through an arc approximately 180 degrees, whereupon the door 12 will be moved out to the position shown in 105 dotted lines in Fig. 2. In this position of the shaft A, the off-set crank pins 21—21 extend over the adjacent edges of the door 12 so that the shaft A cannot, in this position, be moved vertically up and down; 110

therefore it is necessary to swing the shaft A back through approximately an arc of 180 degrees, but without engaging the crank pins 21 with the keepers 24. When 5 swung back to this position, the lever 15 is then pressed downwardly, and on account of the bracket 27 serving as a fulcrum, the shaft A will be raised vertically sufficiently for the lower crank pin 21 to clear the adjacent 10 platform indicated in Fig. 3 at 29, whereupon the door 12 can be swung out over the platform without difficulty. In moving the shaft A vertically, in the manner hereinbefore described, the shoulder 15 on the upper crank member 19 will engage the under side of the bearing 23 to limit the amount of such movement. In closing the doors, the reverse of the operations just described will take place, as will be understood. 15

Although I have herein shown and described specifically one form of my improvements, I am aware that various changes and modifications may be made in 25 the details of construction and arrangement of parts without departing from the spirit of the invention, and all such changes and modifications are contemplated as come within the scope of the claims appended 30 hereto.

I claim:—

1. The combination with a hinged door, of a door operating mechanism therefor comprising a shaft rotatably mounted on said door, said shaft having crank pins at the ends 35

thereof normally extending above and below the door, said shaft being longitudinally slidably mounted relatively to said door whereby the lower crank pin may be moved to a position flush with or above the 40 lower edge of the door to thereby permit the door to be swung out over a platform or the like on a level with the lower edge of the door.

2. The combination with a hinged door, 45 of a door operating mechanism comprising a shaft rotatably and longitudinally slidably mounted on said door, means for shifting said shaft longitudinally of the door, said means including a lever pivotally connected to the shaft, and a fulcrum bracket secured to the door with which said lever is adapted to co-operate.

3. In a refrigerator car, the combination 55 with a hinged door, of a shaft mounted on said door, said shaft having journals at each end thereof, bearings mounted on said door within which said journals are rotatably and longitudinally slidably mounted, a lever pivotally connected to said shaft, and a fulcrum bracket secured to said door and below the normal position of said lever, said bracket serving as a fulcrum for said lever when the latter is swung downwardly to thereby lift the shaft vertically.

GOODRICH Q. LEWIS.
